UNITED STATES PATENT OFFICE.

GEORGE SHEPHERD AND WALTER I. JAMES, OF INDIANAPOLIS, INDIANA, ASSIGNEES
TO OTTO POHLAR, OF INDIANAPOLIS, INDIANA.

BOTTLE CAPPER.

Application filed October 10, 1927. Serial No. 225,215.

This invention relates to bottle cappers, particularly of the hand operated variety and one feature of the invention is the provision of adjustable parts, whereby bottles of different heights may be readily capped by the same machine.

A further feature of the invention is the provision of a flexible union between the cap applying plunger and the lever for operating the same, whereby the cap applying member will always remain in alignment with the neck of the bottle, regardless of the position of the lever.

A further feature of the invention is the provision of suitable guide members for the cap applying member, and a further feature of the invention is the provision of means for readily assembling or disassembling the parts of the device.

Other objects and advantages will be hereinafter more fully set forth and pointed out in the accompanying specification.

In the accompanying drawing, which is made a part of this application,

Figure 1 is a perspective view of the device.

Figure 2 is a detail sectional view thru the upper portion of the capper, and

Figure 3 is a detail transverse sectional view thru the upper portion of the capper, as taken in the proximity of line 3—3 of Fig. 2.

Referring to the drawing, 1 indicates the body portion of the capper, comprising a standard 2, and a base 3, the base extending outwardly from the lower end of the standard, to provide a support for a bottle 4, indicated by dotted lines.

Pivots attached to the upper end portion of the standard 2, by means of a bolt 5 or the like, is a lever 6, the pivoting end of the lever having parallel arms 7, which together straddle the end of the standard. The bolt 5 passes thru said arms 7 and said standard end and serves as a fulcrum for the lever 6. The free ends of the arms 7 are yoked together by a loop formation 8, to which is attached one end of a contraction coil spring 9, the opposite end of the spring being attached to the standard 2, said spring by its contracting tendency serving to normally pull down on the yoke formation 8 and thus keep the lever 6 normally tilted to elevated position as shown in Fig. 1.

Extending laterally from the standard 2 and adjacent the upper end thereof, is a pair of spaced guide lugs 10 and 11, thru which loosely extends a threaded shank 12 and by means of which the shank is caused to travel vertically to the base 3 and in a straight line. The lower end of the shank 12 has a cap applying socket 13 conveniently threaded thereto, while to the upper end of said shank is attached a cross bar handle 14, by means of which the shank may be readily rotated for adjusting the height of the socket 13 with respect to the height of bottle being used, as will be understood.

The shank 12 is threaded thru a nut 15, which nut is positioned between the arms 7 between the bolt 5 and the lever 6, and is flexibly united to said arms by extending trunnions 16 which extend laterally from opposite edges of said nut, and into grooves 17 in the inner faces of the arms 7. Said grooves extend longitudinally of the arms so that said trunnions may slide therein when the lever is swung upwardly or downwardly, thus permitting the arms 7 to travel in an arc-like path, while the nut 15 remains laterally immovable, and the vertical alignment of the shank remains unchanged, although said nut will at the same time be correspondingly raised or lowered by said grooves.

In order that the nut may be readily and easily assembled with the lever and standard, the forward ends of the grooves 17 are directed downwardly at an angle to the lower edges of the arms 7, the forward terminations of the grooves being so located that when the studs 16 have been entered in the grooves and the bolt 5 entered thru the arms, the nut 15 cannot leave its position between the arms, although the lever may be freely swung upwardly or downwardly.

In applying this device to use, the shank 12 is first manually adjusted to adapt it for use with the height of bottle being capped, by manipulation of the handle 14. The bottle is then filled and placed over the base 3 with a cap on same in position to be forced onto the neck of the bottle, as indicated by dotted lines 18. Downward pressure is then applied to the outer end of the lever 6, which will force the socket 13 against the cap 18 and thus bend the outer edges of the cap over the end of the bottle neck. Pressure being then released from the lever, the ten-

sion of the spring 9 instantly elevates the free end of same and releases the socket from the cap 18, so that the bottle may be removed and replaced with another bottle to be 5 capped, and so on.

By mounting the nut 15 in the manner shown, whereby the fulcrum contact between the nut and lever may change as the lever is moved in the arc of a circle, the nut 15 10 will be held from movement in a horizontal direction by the shank 12, which with the socket 13 remains in alignment with the neck of the bottle, if properly placed on the base 3, the guide lugs 10 and 11 assisting in retaining the shank in perfect vertical alignment.

While the description and drawing illustrate in a general way, certain instrumentalities which may be employed in carrying 20 the invention into effect, it is evident that many modifications may be made in the various details, without departing from the scope of the appended claim, it being understood that the invention is not restricted 25 to the particular example herein described.

We claim as our invention:

In a bottle capper, a one piece standard

having a base at one end and a pair of spaced guide lugs near the opposite end thereof, a one piece lever divided at one end to form 30 paralleling arms for straddling the upper end of said standard, the outer ends of said arms being connected together by an integral loop member, a bolt passing laterally through said arms and standard forming a 35 fulcrum for said lever, said arms having grooves in their inner faces part way through said arms, one end of the grooves being directed downwardly to communicate with the lower edges of said arms, a nut between said arms, studs on opposite sides of said nut adapted to enter and have movement longitudinally of said grooves, a shank threaded through said nut, a cap receiving socket on the lower end of said shank, and 40 a spring having one of its ends attached to the loop connection of said lever and its opposite end to said standard.

In testimony whereof, we have hereunto set our hands on this the 5th day of October, 50 1927, A. D.

GEORGE SHEPHERD.
WALTER I. JAMES.
